UNITED STATES PATENT OFFICE.

CHARLES PHILLIPS, OF WICHITA, KANSAS, ASSIGNOR TO WILLIAM H. PHILLIPS, OF WICHITA, KANSAS.

HOUSEHOLD ELECTRIC REFRIGERATOR.

Application filed August 18, 1926. Serial No. 130,008.

This invention relates to refrigerators of that type embodying a brine tank, an expansion coil, compressor, an electric motor for operating the compressor, and a thermostatic switch in the motor circuit for keeping the temperature of the refrigerator within certain predetermined limits.

The present invention has for one of its objects to provide a refrigerator of this character which may be efficiently operated at a comparatively small cost, which may be maintained in a highly sanitary condition with the expenditure of comparatively little labor, and which may be manufactured and sold at a comparatively small cost.

With the foregoing and other objects in view, the nature of which will become apparent as the description proceeds, the invention consists of the novel construction, combination and arrangement of parts hereinafter fully described and claimed, and illustrated in the accompanying drawings, wherein:

Figure 1 is a sectional view taken on a plane extending vertically and centrally through a refrigerator constructed in accordance with my invention,

Figure 2 is a sectional view on an enlarged scale taken on the vertical plane indicated by the line 2—2 of Figure 1,

Figure 3 is a sectional view on an enlarged scale taken on the vertical plane indicated by the line 3—3 of Figure 1,

Figure 4 is a sectional view on an enlarged scale taken on the horizontal plane indicated by the line 4—4 of Figure 1,

Figure 5 is a sectional view on an enlarged scale taken on the horizontal plane indicated by the line 5—5 of Figure 1,

Figure 6 is a detail sectional view taken on the plane indicated by the line 6—6 of Figure 4,

Figure 7 is a detail sectional view taken on the plane indicated by the line 7—7 of Figure 5,

Figure 8 is a detail sectional view of one of the shelf supporting brackets,

Figure 9 is a detail sectional view taken on the plane indicated by the line 9—9 of Figure 3 and illustrating the manner in which the shelf supporting frames are connected to the bracket, and

Figure 10 is a detail perspective view il-

lustrating the means through the medium of which the shelf supporting frames are detachably connected together.

Corresponding and like parts are referred to in the following description, and designated in the several views of the accompanying drawings, by similar reference characters.

The refrigerator comprises a cabinet which is of upright cylindrical formation. The cabinet consists of relatively spaced inner and outer side walls 1 and 1^a, relatively spaced inner and outer top walls 2 and 2^a, and relatively spaced inner and outer bottom walls 3 and 3^a. These walls are made of noncorrosive metal, such as stainless steel, and positioned between them is insulation 4. The insulation 4 is made up of pressed cork rings 4^a, which are located between the side walls 1 and 1^a and are connected by ship-lap joints 4^b. The top and bottom portions 4^c and 4^d of the insulation, which portions are located between the top walls 2 and 2^a and the bottom walls 3 and 3^a, are formed integrally with the top and bottom rings 4^a so as to avoid joints in the insulation at the corners of the cabinet. The inner surface of the cabinet is perfectly smooth, and the walls 1, 2 and 3 are connected by rounded portions as shown at 5, whereby to permit the cabinet to be easily maintained in a highly sanitary condition.

The top of the cabinet is provided with a central opening in which is removably positioned a main lid 6, and said lid is provided with a central opening in which is removably positioned an auxiliary lid 7. The top walls 2 and 2^a are provided, at the opening formed therein for the reception of the lid 6, with annular flanges 8 which, together with screws 8^a, hold a fiber ring 9 in place between said walls. The fiber ring 9 extends between the flanges 8 to insulate the top walls 2 and 2^a, and said ring extends slightly beyond the outer face of said flanges to form a non-metallic seat for the lid 6. The lid 6 comprises inner and outer plates 6^a and 6^b of non-corrosive metal, and positioned between said plates are an insulating pressed cork ring 6^c and insulating fiber rings 6^d and 6^e. The rings 6^d and 6^e are retained in place by flanges 6^f and screws 6^g, which latter by reason of their

engagement with the rings hold the plates 6^a and 6^b together. The rings 6^d and 6^e extend between the flanges 6^f to insulate the plates 6^a and 6^b, and project beyond the outer faces of said flanges. The ring 6^d by reason of its extension beyond the outer edge thereof, provides the lid 6 with a non-metallic part for contact with its seat. As the ring 6^e extends beyond the inner edge of the lid 6, it provides a non-metallic seat for the lid 7. The lid 7 is similar to the lid 6, and the fiber ring thereof is designated 7^a and the insulation 7^b. The ring 7^a provides the lid 7 with a non-metallic side for contact with its non-metallic seat carried by the lid 6. As the plates 2 and 2^a of the top of the cabinet are thoroughly insulated, as the metal parts of the lids 6 and 7 are also thoroughly insulated, and as no metal parts of said top and lids are in contact, there is no possibility of heat being conducted to the interior of the cabinet.

The lids 6 and 7 are provided with hollow annular flanges 10 and 11, respectively, of which the former overlies the top of the cabinet and the latter overlies the lid 6. Hollow elastic gaskets 12 and 13 are positioned in the flanges 10 and 11, respectively, and contact with the top of the cabinet and the top of the lid 6, and said gaskets function in conjunction with the fiber rings 9, 6^b, 6^c and 7^a, to exclude heat from the interior of the cabinet.

Brackets 19 are suspended from the lid 6 by means of rods 20, and supported thereby is the brine tank 21 of the cooling system of the refrigerator. The brine tank 21 has a central compartment or brine chamber 22 which is open at its top and is provided for the reception of an ice cream freezer and deep pans or molds for the making of ice. The brine tank 21 also has an annular chamber 23 which surrounds the compartment 22 and is open at its bottom. The provision of the brine tank 21 with the chamber 23, provides it with the maximum heat absorbing surface. An ice cream freezer or pans or molds may be placed in the compartment 22 through the opening in the lid 6, and to exclude odors from this compartment there is provided a cylindrical partition 24 which extends from the top of the brine tank 21 to the bottom of the lid 6. The partition 24 is secured to the lid 6 and brine tank 21, cuts off all communication between the brine chamber 22 and the interior of the cabinet, and assists the rods 20 to support the brine tank. An operating shaft 25 for the ice cream freezer 25^a, which may be of any well known or appropriate construction is journaled in the lid 7, and may if desired be turned by hand. It is preferred, however, to provide an electric motor 26 for turning the shaft 25. The motor 26 is mounted upon the top of the cabinet, and the ar-

ture shaft 27 thereof is provided with a worm 28 which meshes with a worm wheel 29 fixed to the shaft 25. A switch, not shown, for starting and stopping the motor 26, may be mounted upon any suitable part 70 of the cabinet. The shaft 25 is carried by a ball bearing 25^b located within the lid 7, and the lower end thereof is detachably engaged with the stirrer staff 25^c of the freezer 25^a as shown at 25^d.

To adapt the refrigerator for cooling drinking water, a coil 30 is provided. The coil 30 surrounds the brine tank 21 and communicates at its upper end with a cup 31 mounted upon and secured to the top of the cabinet. The lower end of the coil 30 communicates with a faucet 32 which is located at a side of the cabinet directly above a glass supporting shelf 33. A reservoir 34 for the drinking water, which is in the form 85 of a bottle, has the neck thereof positioned in the cup 31.

In addition to the brine tank 21, the cooling system for the refrigerator comprises an expansion coil 35, a condenser coil 36, a 90 compressor 37 and a liquid receiver 38. All these parts with the exception of the coil 35, are together with an electric motor 39 for operating the compressor 37, mounted below the cabinet which to permit of this being done is supported by legs 40 provided with castors 41. The coil 35 is mounted in the brine tank 21, and an expansion coil 35^a is mounted in the brine compartment 22. 42 designates the liquid line which extends from the liquid receiver 38 to the expansion coils 35 and 35^a, and at its point of connection with the coils there is provided an expansion valve 35^c. 43 designates the vapor return line which extends from the coils 35 and 35^a to the compressor 37. 45 is the connection between the condenser coil 36 and liquid receiver 38. The make and break switch for the motor 39 is mounted in a case 46 positioned below the cabinet, and the thermostat 47 by which this switch is controlled to keep the temperature of the refrigerator within certain predetermined limits, is mounted in a compartment 47^a formed by offsetting a part of the partition 24 and is accessible through the opening in the lid 6. The make and break switch and thermostat, both of which may be of any well known or appropriate construction, are connected by a line 48.

The motor 39 is connected to the compressor 37 by means of a counter shaft 49, a rack 50 provided with upper and lower series of teeth 51 and 52, respectively, and a mutilated pinion 53 adapted during one 125 phase of each rotation thereof to engage the rack teeth 51 and during another phase of each rotation thereof to engage the rack teeth 52 and thus impart a continuous reciprocatory movement to the rack 50. The 130

rack 50 is connected directly to the piston rod 54 of the compressor 37, and is supported by a casing 55 removably connected to the stuffing box 56 of the compressor. 5 The casing 55 is adapted to contain oil to lubricate the rack 50 and pinion 53. The shaft 49 is driven from the armature shaft 57 of the motor 39 by a belt 58 of the V-type which passes about a pulley 59 fixed to the 10 shaft 57 and a larger pulley 60 fixed to the shaft 49.

Access to the food compartment of the refrigerator is gained by way of one comparatively small opening 61 which is closed 15 by a door 62 having inner and outer transparent panels 62^a and 62^b to permit the contents of the food compartment to be seen without opening the door. The panels 62^a and 62^b are secured to a metal frame 62^c, 20 the inner and outer walls of which are insulated from each other. The contents of the food compartment is supported by shelves 63 which are of sectional formation and detachably secured to a vertically disposed shaft 64. The shaft 64 is supported at its upper and lower ends by ball bearings 65 and 66, respectively. The bearing 65 is carried by a casing 67 for bodily movement in an axial direction whereby to permit the 25 ready application and removal of the shaft 64. The casing 67 is secured to a drip pan 67^a and is provided at its lower end with a removable split ring 68 for supporting the bearing 65. The bearing 65 is held against 30 casual upward movement, in which direction it must be moved to effect the release of the upper end of the shaft 64, by a spring 69.

The sides 1 and 1^a are provided at the door opening 61 with flanges 1^b and 1^c which 35 support a fiber gasket 1^d which projects beyond the flanges to provide a non-metallic seat for the door 62, and the door is provided with a fiber gasket 62^a which projects beyond the edges thereof for contact 40 with said seat.

As the metallic parts of the cabinet, lids 6 and 7 and door 62 do not contact there is no possibility of heat being conducted into the cabinet about the lids and door. In view 45 thereof, as the inner and outer walls of the cabinet, lids 6 and 7 and door 62, are thoroughly insulated, and in view of the small size of the door opening 61, it is possible to efficiently operate the refrigerator without 50 maintaining the cooling unit at a temperature so low as to result in the drying up of the contents of the refrigerator. This prevents the moisture in the refrigerator from 55 congealing on the cooling unit, and maintains the refrigerator at the desired humidity as well as temperature.

The shelves 63 are circular and sectional. Each shelf section comprises a frame 63^a of sector formation to which is secured a per- 60 forated plate 63^b or shelving wire, and a dia-

metrical rib 63^c which extends inwardly beyond the inner end of the shelf section. The inner ends of the frames 63^a rest upon the shoulders 70 of collars 70^a which are secured to the shaft 64, and the inner ends of the 70 ribs 63^c enter vertical grooves 70^b in the collars. The collars 70^a are provided at the upper ends of the grooves 70^b with shoulders or lugs 70^c which engage in recesses 63^d in the inner ends of the ribs 63^c so as to prevent 75 the shelf sections from being accidentally disconnected from the collars 70^a. The collars 70^a are secured to the shaft 64 by set screws 71, and may be adjusted vertically on the shaft so as to support the bottom shelf 80 63 at any desired distance from the bottom of the cabinet and the top shelf 63 at any desired distance from the bottom shelf. The frames 63^a are secured together by pins 63^e which removably pass through interfitting 85 eyes 63^f on the sides of the frames. To remove the shelves 63, it is only necessary to withdraw the pins 63^e, tilt the outer ends of their sections upwardly so as to disengage the ribs 63^c from the shoulders 70^c, and there- 90 after withdraw the sections through the door opening 61. After the shelves 63 have been removed, the shaft 64 may be removed by first moving it upwardly so as to withdraw the bearing 66, which is secured thereto and 95 removably positioned in depression 66^a in the bottom of the cabinet, this being possible due to the fact that the bearing 65 is held in active position by the spring 69. After this has been done, the shaft may be readily 100 withdrawn through the door opening 61 in a manner that should be apparent. After the removal of the shelves 63 and shaft 64, the entire inner surface of the cabinet is 105 freely accessible and free of brackets and the like, and due thereto said surface may be readily cleaned.

All moisture accumulating on the brine tank 21 falls into an annular pan 76 and a cylindrical pan 76^a which latter is in communication with the upper end of the hollow shaft 64. Troughs 76^b extend from the pan 76 to the pan 76^a and convey water from the former to the latter. The troughs 76^b are positioned directly below the brackets 110 115 19 so as to catch any moisture dripping therefrom. The bottom portion 21^a of the brine tank 21 slopes downwardly and outwardly in the direction of the pan 76, and the bottom portion 21^b of the brine tank 120 slopes in the direction of the center of the pan 76^a, whereby to direct all moisture accumulating on the brine tank into the pans. A drain nipple 77 extends through the bottom of the cabinet in alignment with the 125 shaft 64. A water seal of any well known or appropriate construction will be connected to the nipple 77.

In order to permit the shelves 63 to be readily turned without opening the door 62, 130

a shaft 78 is geared as at 79 to the shaft 64 and is provided at its outer end with a hand crank 80.

From the foregoing description, taken in connection with the accompanying drawings, the advantages of the construction of the refrigerator will be readily apparent to those skilled in the art to which it appertains. While I have described the principles involved in the refrigerator, together with the structure which I now consider to be the best embodiment thereof, I desire to have it understood that the device shown is merely illustrative, and that such changes may be made when desired as are within the scope of the invention as claimed.

What is claimed is:

1. A refrigerator comprising a cabinet having an opening in the top thereof, a closure for the opening and provided with an opening, a closure for the opening in the first named closure, a cooling system including a brine tank arranged within the cabinet and having a brine chamber open at the top, and a partition surrounding the chamber and extending from the upper side of the tank to the under side of the second named closure.

2. A refrigerator comprising a cabinet having an opening in the top thereof, a closure for the opening, a cooling system including a brine tank having a brine chamber open at the top and registering with said opening in the cabinet, a partition surrounding the brine chamber and opening and extending from the top of the tank to the top of the cabinet and secured to said parts, rods secured to the top of the cabinet, and brackets secured to the rods and upon which the tank rests.

3. A refrigerator comprising a cabinet provided with an opening in its top wall, a cooling unit arranged within the cabinet in spaced relation to said wall thereof, said unit being provided with a chamber registering with the opening in the top wall of the cabinet, and a partition extending from the top of the unit to the top wall of the cabinet and surrounding said opening in the cabinet and the open side of the chamber, said partition constituting suspending means for the unit and cutting off communication between the interior of the cabinet and said opening and chamber.

In testimony whereof I affix my signature.
CHARLES PHILLIPS.
